(57) **CLAIM**

The ornamental design for a napkin holder, as shown and
described.

DESCRIPTION

FIG. 1 is a perspective view of a napkin holder, showing our
new design;

FIG. 2 is a front view of the napkin holder of FIG. 1;
FIG. 3 is a side view of the napkin holder of FIG. 1;
FIG. 4 is a top view of the napkin holder of FIG. 1; and,
FIG. 5 is a bottom view of the napkin holder of FIG. 1.
The broken line portions show unclaimed subject matter
only and form no part of the claimed design.

1 Claim, 4 Drawing Sheets
